United States Patent Office

Des. 176,136
Patented Nov. 22, 1955

176,136

PLATE OR SIMILAR ARTICLE

Takeshi Inoue, Atsuta-ku, Nagoya, Japan, assignor to
Noritake Co., Inc., New York, N. Y., a corporation of
New York

Application December 3, 1954, Serial No. 33,385

Term of patent 7 years

(Cl. D44—15).

The figure is a plan view of a plate or similar article, showing my new design.

A design unit of the outer border on the surface of the plate is shown in full lines, and a unit of the inner design of the border is also shown in full lines, but each of the units of the design at the border is set off by its own respective boundaries by broken lines, beyond which each design repeats as indicated around the circumference of the plate beyond the broken line boundary of each design unit.

The plate is of a conventional configuration when viewed from the side and bottom thereof.

I claim:

The ornamental design for a plate or similar article, substantially as shown and described.
